ANIMAL FIGURE SEAT FOR PLAYGROUND APPARATUS

Steven A. Henning and Philip G. Miller, Anderson, Ind., assignors to American Playground Device Co., Anderson, Ind.

Filed Apr. 23, 1970, Ser. No. 22,593

Term of patent 14 years

Int. Cl. D21—04

U.S. Cl. D34—15

FIG. 1 is a side elevation of an animal figure seat for playground apparatus showing our new design;

FIG. 2 is a front elevation thereof; and

FIG. 3 is a top plan view thereof.

We claim:

The ornamental design for an animal figure seat for playground apparatus, as shown.
